MATCH EQUIPPED CIGARETTE

Ingolf Melvin Stensvad, Redwood Falls, Minn.

Application February 18, 1937, Serial No. 126,388

1 Claim. (Cl. 131—52)

My invention relates to cigarettes as packed and distributed in paper containers and provides for each cigarette a match attached thereto in a novel way, whereby there is not only a match provided for the lighting of each cigarette, but simple and efficient means for easily removing the cigarettes from the package without damage to the cigarettes.

The invention is illustrated in the accompanying drawing, wherein like characters indicate like parts throughout the several views:

Referring to the drawing:

Fig. 1 is a side elevation showing a package of cigarettes with the matches attached thereto in accordance with my invention, some parts of the container being broken away;

Fig. 2 is a side elevation of one of the removed cigarettes with attached match;

Fig. 3 is a front elevation of the cigarette and match shown in Fig. 2;

Fig. 4 is a side elevation of one of the cigarettes, the original position of the match being indicated by dotted lines; and

Fig. 5 is a side elevation of the detached match.

The cigarettes 6, which, in themselves, are of the usual construction, are contained in the customary paper container 7, which latter is preferably provided on one surface, such as its bottom, with a friction surface 8 for the lighting of the matches.

The matches, which are preferably of the so-called "safety" type, comprise the customary body portions 9 equipped at one end with the ignition head 10. The manner of attaching these matches to the cigarettes is highly important. Each match is attached to a cigarette with its ignition head 10 located close to one side of the intermediate portion of the cigarette, and with

its stem end projecting at 9a slightly beyond the end of the cigarette. The match stem is attached to the side of the upper end of the cigarette, as indicated at 11, by adhesive material.

When the container is closed, the match ends 9a will be under the cover, but when the cover is opened, as shown in Fig. 1, there will be a tendency for the cigarettes to move so as to project the match ends 9a. At any rate, these match ends 9a, that are removed from the ignition heads 10, will always be available for engagement by the fingers to pull the proper cigarette out of the container without damaging either the removed or adjacent cigarettes. In these manipulations, the ignition heads 10 are not at any time engaged by the fingers, and hence, they will not be damaged even if the fingers should be wet or moist.

When the cigarette has been removed, the match may be ignited and used to light the cigarette. Of course no attempt should be made to light the match while it is attached to the cigarette. In actual practice the matches will lie very close to the cigarettes and the cigarettes should be turned so that the heads 10 will come in the more or less open spaces between the closely packed cigarettes.

In actual practice the invention illustrated has been found to be very convenient and desirable for the reasons stated and for other reasons.

What I claim is:

A cigarette having attached thereto, at one end only, the butt end of a match, with said butt end projecting beyond that end of the cigarette and with the ignition head of the match in loose contact with the intermediate portion of said cigarette, said match being directly secured to the cigarette by adhesive means.

INGOLF MELVIN STENSVAD.
